(57) **CLAIM**

The ornamental design for a tire for a car, as shown and described.

DESCRIPTION

FIG. 1 is a perspective view of the tire for a car, particularly showing the inventive design thereof;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged partial view thereof; and,

FIG. 9 is a fragmentary sectional view taken along the line depicted in FIG. 8.

In the drawings, FIGS. 1–8 schematically depict the tread, and for clarity, FIG. 9 depicts the depth of the tread grooves.
